GRAIN DOOR OPENER

Thomas A. Martin, Fort Worth, Tex., assignor to
 Lone Star Elevators, Fort Worth, Tex., a corporation of Texas

Application October 21, 1940, Serial No. 362,161

3 Claims. (Cl. 254—127)

This invention relates to a device for opening doors of grain cars, which consist generally of wooden planks positioned vertically within the door jambs extending across the door opening and nailed from the inside to the jambs.

To open such doors heretofore very complicated devices have been used, or alternatively a simple crow bar and man power.

The object of the present invention is to provide a simple cheap portable device which can be readily handled by one man in combination with a hoist tackle and which has proven very efficient.

The invention consists in the novel construction, arrangement, and combination of parts hereinafter more particularly described and claimed.

One sheet of drawing accompanies this specification in which like reference characters indicate like parts throughout.

Figure 1 is a side view of the improved device as applied to a grain car door, preliminary to opening same;

Figure 2 is a horizontal view looking downward on Figure 1;

Figure 3 is a longitudinal vertical cross-section taken on line 3—3 of Figure 2;

Figure 4 is a vertical cross-section taken on line 4—4 of Figure 1; and

Figure 5 is a fragmentary vertical cross-section of the door engaging end of the device at the end of the door lifting movement.

Referring to the drawing, C represents the car floor, D the car door, and J the door jamb. Adjacent the car is shown a platform I, known as an island at grain elevators, upon which is a fixed post P.

To open the door D it is necessary that the same be pressed inwardly against the grain sufficiently to draw the nails which have fastened its ends to the door jamb J, and after it has reached this inward position that the door be lifted vertically to permit the grain to escape beneath its bottom edge and the car door. To accomplish

this object a toggle device is provided, having at one end a clamp I adapted to embrace the fixed post P and carrying a pivot cam lever 2 by means of which it can be located in position on the post. The clamp I has outwardly directed lugs 3 to

which is hingedly connected a channel shaped member 6 by means of bolt 4. Slidably positioned within members 6 is a second channel member 5 having in its side walls a plurality of aligned openings 8, by means of which, and a bolt 7, the member 5 can be longitudinally ex-

tended with respect to member 6 to vary the effective lengths of member 5. A bracing member 9 is secured between the side walls of member 6 and extends beyond its end carrying on its outermost end downwardly directed lugs 10 adapted to guide and brace member 5. On the outer end of member 5 are positioned lugs 11 between which is pivotally secured a length 12 having at its free end an eye 13 adapted to receive the hook of a block and tackle hoist device. A second channel member 14 is pivoted at one end as by bolt 15 to member 5 intermediate the latter's ends and between the side walls of the free end of member 14 is pivoted by bolt 16 a gaff link 17 having an outwardly directed prong 18 adapted to engage the car door. A handle 19 is provided near the free end of member 14 for preliminarily positioning the device on the door.

In operation the car to be opened is drawn up beside an island I, with the door adjacent a fixed post P, and the door opening device preliminarily adjusted by means of bolt 7 to the distance between the post and the car door. Members 5 and 14 are then hinged angularly as indicated in full lines in Figure 1, and the clamp I secured to the fixed post, while the gaff link 17 is brought into contact with the car door.

A block and tackle is then applied to link 12 and upon hoisting the free end of member 5 the members 5 and 14 straighten and in so doing force the car door inwardly pulling the nails from the jamb J which, by the time the arms 5 and 14 are in alignment, are clear of the jamb. Further hoisting on the block and tackle lifts the door clear of the floor permitting the grain to escape between its lower edge and the car floor.

Various modifications will readily suggest themselves to those skilled in the art to provide proper strength and rigidity to the various members of the device but all within the scope of the present invention as claimed.

Having thus fully described my invention, I claim:

1. A car door opener comprising an arm, means at one end to engage a fixed post or the like, means at the other end to receive a hoisting tackle, a second arm pivoted by one end to the first at a point intermediate its ends, and a gaff link pivoted at the free end of the second arm.

2. A car door opener comprising an arm, a port engaging clamp pivoted at one end of the arm, means at the other end of the arm to receive a hoisting tackle, a second arm pivoted by one end at a point intermediate the ends of the first arm and of a length longer than that part of the

- first arm between the pivot and its tackle engaging end, and a link pivoted on the free end of the second arm having an outwardly directed prong.
5. 3. A tool for opening the doors of grain cars, comprising a clamp adapted to engage a fixed post or the like, means for removably engaging

the face of the car door and toggle means comprising pivoted members, one of said members pivotally associated with the clamp and the other pivotally associated with the door engaging means.
